Primary Examiner—Pamela J. Burgess

(74) Attorney, Agent, or Firm—Darby & Darby P.C.

(57) **CLAIM**

The ornamental design for a insert plate for a handy mop, as shown and described.

DESCRIPTION

FIG. 1 is a perspective view of an insert plate for a handy mop;
FIG. 2 is a front view thereof;
FIG. 3 is a side view thereof;
FIG. 4 is a back view thereof;
FIG. 5 is a top view thereof; and,
FIG. 6 is a bottom view thereon.
